UNITED STATES PATENT OFFICE.

AMOS W. THOMAS, OF PHILADELPHIA, PENNSYLVANIA.

DESIGN FOR BUSTLES.

Specification forming part of Design No. 5,266, dated September 12, 1871.

To all whom it may concern:

Be it known that I, AMOS W. THOMAS, of Philadelphia, in the county of Philadelphia and State of Pennsylvania, have invented a new and original Design for a Bustle; and I do hereby declare that the following is a full, clear, and exact description thereof, which will enable others skilled in the art to make and use the same, reference being had to the accompanying drawing forming part of this specification.

The drawing represents a side view of my new design for a bustle.

In the drawing, A represents the belt of the

bustle. B B are the hoops, and CC the supporting-springs of the hoops. Each spring C has a straight or curved inner part, *a*, which is fastened near its upper end to the belt, and a curved outer part, *b*, to which the hoops are fastened. In this manner the requisite bulge for the hoops is obtained.

I claim as my invention—

The design for the supporting-springs of a bustle, as shown.
